UNITED STATES PATENT OFFICE.

WILLIAM H. TRUITT, OF BLOOMFIELD, NEW JERSEY.

TIE PRESSER.

Application filed March 13, 1924. Serial No 699,013.

To all whom it may concern:

Be it known that I, WILLIAM H. TRUITT, a citizen of the United States, residing at Bloomfield, in the county of Essex and 5 State of New Jersey, have invented certain new and useful Improvements in Tie Pressers; and I do declare the following to be a full, clear, and exact description of the invention, such as will enable others skilled 10 in the art to which it appertains to make and use the same.

My invention relates to improvements in pressing devices for articles of apparel, such as coat sleeves, trouser legs, neckties, etc., 15 and the present disclosure is directed to a device which is designated primarily for pressing neckties, although when made in larger sizes, it could be advantageously used for pressing other articles of apparel. 20 The device is of the type which is inserted into the article to be pressed and consists of a pair of substantially flat, elongated strips of metal or other desired material, and means for exerting outward force on 25 said strips, so as to tightly stretch the article of apparel around them, to remove all wrinkles, the pressing operation being facilitated by dampening of the article.

One object of the invention is to provide 30 a novel form of spring connection between the two strips, which connection acts not only to exert outward stress on said strips, but acts to guide the inward and outward movements of these strips, as well as to 35 retain them in substantially a common plane.

Another object of the invention is to provide 40 a spring device for exerting outward stress on said strips, which device also acts as means for effectively guiding the presser into the article to be pressed.

A still further aim is to provide a device 45 of the class described which may be easily and inexpensively manufactured and marketed, yet will be highly efficient and generally desirable.

With the foregoing in view, the invention resides in the novel subject matter herein-after described and claimed, the description 50 being supplemented by the accompanying drawing.

Figure 1 is a perspective view of the invention within a necktie.

Figure 2 is a plan view of the presser removed from the tie.

Figure 3 is a plan view, partly broken

away, showing the presser in a relatively narrow tie, with the two strips in overlapping relation.

Figures 4 and 5 are transverse sectional views as indicated by lines 4-4 and 5-5 of Figs. 2 and 3 respectively.

In the drawing above briefly described, the numerals 1 designate a pair of elongated strips which are preferably formed of metal, 65 the outer edges of these strips being preferably rounded as shown in Fig. 5, while their inner edges may be turned laterally to some extent or otherwise beveled as indicated at 2, so that said strips may be easily 70 moved into overlapping relation, either when inserting a device into a tie or the like, or when the article being pressed is of such size as to necessitate that the strips be overlapped, as shown for instance in Figs. 3 75 and 5.

A novel form of spring device 3 connects adjacent ends of the strips 1, two of these spring devices being shown, and as they are identical in construction, with the exception 80 of size, a description of one will suffice for both. In forming the spring devices 3, I take a single length of wire and bend it to form a substantially U-shaped intermediate portion 4 whose arms 5 converge to a 85 point 6 spaced outwardly from one end of the strips 1, the arm-connecting part 7 of the portion 4, and the inner ends of the arms 5, lying against one side of the strips 1, as shown. At the point 6, the end portions of the wire cross each other and said end portions are then bent inwardly toward the strips 1, as indicated at 8, providing a pair of 90 inwardly extending arms 9 which are disposed in outwardly spaced substantially 95 parallel relation, with the arms 5. The free end of the arms 9 are bent laterally toward each other as indicated at 10 and soldered or otherwise secured to the ends of the strips 1, 100 clearly shown in the drawing.

The arm connecting parts 7 of the two spring devices 3 are preferably straight and it will be seen that as the strips 1 are forced inwardly or outwardly, they slide along said 105 parts 7 and at the same time, the ends 10 of the spring wires, slide across the arms 5. Thus, the strips 1 are generally steadied and guided in their inward and outward movement, and are held in substantially a common plane. Attention may also be directed 110 to the fact that the arms 9 at the smaller

end of the pressing device (the latter being preferably tapered) act as means for guiding this device into the necktie or other article to be pressed. It will be seen that as 5 these arms converge outwardly, they act to spread the article into which the device is being inserted, thus greatly facilitating the insertion.

By constructing the device in the manner 10 shown and described, or in an equivalent manner, it will be seen that it will not only be simple and inexpensive, but that it will be generally efficient and desirable. As excellent results have been obtained from the 15 details disclosed, they may well be followed, but within the scope of the invention as claimed, numerous minor changes may be made.

I claim:—

20 A stretching device of the character described comprising a pair of elongated sub-

stantially flat strips arranged alongside of each other in approximately the same plane, and a pair of substantially flat coiled springs 25 for forcing said strips apart arranged in approximately the same plane with said strips and having portions extending beyond the ends of the latter, said springs being secured at their ends to the ends of said strips and constituting the sole means of 30 securing said strips together, the portions of said springs which extend beyond the ends of said strips being arranged in converging relation in order to guide said strips into the apparel to be stretched and the coils of said springs being arranged in overlapping relation with the inner edges of said strips 35 at the ends thereof to maintain said strips in approximately the same plane.

In testimony whereof I have hereunto affixed my signature.

WILLIAM H. TRUITT.
